PARK BENCH

Robert E. Everly, Winnetka, Ill., assignor to Game-Time,
Inc., Litchfield, Mich., a corporation of Michigan

Application May 26, 1958, Serial No. 51,085

Term of patent 14 years

(Cl. D15—11)

Fig. 1

Fig. 1 is an end elevational view of a park bench showing my new design as taken from the left end of Fig. 2, having portions broken away to show indeterminate length;

Fig. 2 is a front elevational view thereof, having portions broken away to show indeterminate length; and

Fig. 3 is a perspective thereof as taken from the upper left side of Fig. 2, having portions broken away to show indeterminate length.

I claim:

An ornamental design for a park bench, as shown and described.
